UNITED STATES PATENT OFFICE.

OTTO STECHHAN, OF INDIANAPOLIS, INDIANA.

RECLINING-CHAIR.

SPECIFICATION forming part of Letters Patent No. 296,478, dated April 8, 1884.

Application filed May 15, 1883. (No model.)

To all whom it may concern:

Be it known that I, OTTO STECHHAN, of the city of Indianapolis, county of Marion, and State of Indiana, have invented certain new and useful Improvements in Reclining-Chairs, of which the following is a specification.

My said invention consists in certain improvements in the construction of reclining-chairs, whereby they are adapted to be easily manipulated, as will be hereinafter more particularly described and claimed.

Referring to the accompanying drawings, which are made a part hereof, and on which similar letters of reference indicate similar parts, Figure 1 is a side elevation of the framework of a chair embodying my invention; Fig. 2, a central vertical section of the same; Fig. 3, a section of a portion of the frame-work and of one of the side pieces of the reclining back of the chair on the dotted line $z z$ in Fig. 4; Fig. 4, a section on the dotted line $y y$ in Fig. 3; Fig. 5, a detail side elevation similar to a portion of Fig. 1; and Fig. 6, a vertical sectional view, looking to the right from the dotted line $x x$.

In said drawings, the portions marked A represent the frame-work of the chair; B, the adjustable reclining back; C, the rack-bars by which said back is secured in position; D, a swinging foot-rest, and E a bar connected to the back B, which operates said foot-rest.

The frame-work A is of a solid and suitable construction, adapted to receive the upholstering and sustain the other portions of the chair. The arms A' thereof are hinged to the front uprights by hinges a' , and have the devices A² secured thereto at the rear ends. Said devices A² have catches a^3 , with which the rack-bars C engage, and hooked ends a^4 , which extend down and engage with the pins a^5 . These ends a^4 extend down on each side of the rear standards of the frame, and thus hold the arm A' from any sidewise movement. Said pins a^5 extend through the rear uprights of the frame-work, and serve both as rests for the rack-bars and, through the devices A², to limit the upward movement of the arms A'.

The back B is an ordinary reclining back, sustained in position by the rack-bars C, and preferably mounted in socket-joints or bearings in the frame-work A, where it is secured in position by pivot-bolts or screws b, which

are sustained by metal straps or plates a^2 , which project upwardly from the frame A. A portion, B', is secured to the inner side of each 55 of the side pieces of the back B, and extends down to a proper point to connect with the rod E.

The rack-bars C are connected to the sides of the back B by pins or bolts b' , and pass 60 through slots or mortises a , formed to receive them in the rear standards of the frame A. They are notched in the usual manner of a ratch, as is shown most plainly in Fig. 3, and are thus adapted to engage with the catches 65 a^3 on the devices A². They are also provided with slots c , extending through the greater portion of their length, which pass over the pins a^5 . Said pins prevent any appreciable vertical movement of these rack-bars at this 70 point, and thus insure that the catches shall promptly engage therewith or be disengaged as the arms A' are lowered or raised.

The swinging foot-rest D is hinged to the frame A, at the front edge of the seat portion, 75 by hinges d , and is caused by the back B, through the rod E, to assume varying positions corresponding to the positions of said back.

The rod E is secured at one end to the portion B' of the back B by a pivot, e. Its other 80 end rests upon a cross-bar of the frame A, and bears an anti-friction roller, e', which rests against the under side of the foot-rest D. As the back B is swung back and forth said foot-rest, through this bar, is operated in a corresponding manner. The anti-friction truck e' causes it to operate easily, and, there being no other connection between the rod E and the foot-rest D, permits said foot-rest to be moved independently of said rod, when desired.

My said chair is easily managed, it being only necessary for the occupant to lean forward to raise the back and to raise the arms A' slightly, so that the notches in the rack-bars C will become disengaged from the catches a^3 , 95 and lean back to give it a greater inclination. It is also simple and inexpensive to manufacture.

Having thus fully described my said invention, what I claim as new, and desire to secure 100 by Letters Patent, is—

1. The combination, in a reclining-chair, of the frame-work A, the reclining back B, the notched bars C, the arms A', hinged to the

front uprights of said frame-work and extending back and resting upon the rear uprights thereof, and catches upon the under side of said arms, which enter the notches in said bars when said arms are in lowered position, and are withdrawn from said notches by raising the arms, substantially as shown and specified.

2. The combination, in a reclining-chair, of the frame-work, the back, the rack-bars having longitudinal slots therein, pins extending through the rear uprights of said frame-work and said rack-bars, hinged arms, and catches on said arms which engage with the notches in said rack-bars, substantially as shown and specified.

3. The combination of the frame-work, the back, the rack-bar, the hinged arm A', the device A², having catch a³, and hooked portions a⁴, and pins a⁵, extending through the rear uprights of said frame-work, and adapted to engage with said hooked portions a⁴, substantially as set forth. 20

In witness whereof I have hereunto set my hand and seal, at Indianapolis, Indiana, this 10th day of May, A. D. 1883.

OTTO STECHHAN. [I. S.]

In presence of—

C. BRADFORD,
CHAS. L. THURBER.
